METHOD OF PRESERVATION

Allison F. H. Scott, Pleasantville, N. Y.

Application April 12, 1933, Serial No. 665,694

1 Claim. (Cl. 27—22)

This invention relates to methods of preservation and more specifically to vaults of air-seal type; it consists in provision whereby an air-seal vault is rendered more effective in the protection of a buried body from the access of water.

In the accompanying drawing a burial is illustrated in vertical section, transversely through the vault, and to this drawing reference will be made in the ensuing specification.

10 The vault of air-seal type typically includes a base or floor-plate, near the margin of which rises to substantial height (say of five inches, more or less) a continuous flange, itself imperforate and imperforate in its union with the base-plate. Support is ordinarily provided within the vault for sustaining a body (contained, ordinarily, within a casket) elevated at an interval above the base or floor-plate, and such support may consist in bars extending from the flange on either 20 side, transversely of the floor-plate.

Associated with the flanged floor-plate, and forming with it the entire vault, is the cover, whose margin is so shaped and proportioned that, when applied, the margin, resting upon the floor-plate, will throughout all its extent encircle the flange.

When the floor-plate has been set in the bottom of a grave, and a body (contained ordinarily within a casket) has been lowered to place upon the floor-plate, and the cover has been applied, a body of air is entrapped beneath the cover; and, should the burial be made in ground liable to become water-soaked, and should water accumulate, after burial has been completed, and stand 30 at a level higher than the level of the base-plate, a level high enough (in the absence of preventive means) to gain access to the body within the casket, the flange surrounded by the margin of the cover will be found to be an effective seal: 40 the body of air entrapped within the vault, compressed by the rising tide of water, will afford restraint upon rise, and will thus afford protection to the buried body.

The invention consists in employing, in association with such a vault of air-seal type, means for generating within the vault, after the vault has been closed, additional volumes of gas, to reinforce the pneumatic pressure within, and thus to render the air-seal more effective. The gas-generation contemplated will ordinarily be of relatively slow progress, to the end that the consequent increase of internal pressure shall occur when and not until occasion arises to render the access useful.

55 Furthermore, I may employ materials such that

the gas generated for the purpose described shall have preservative value of its own, apart from such pressure effect as has been described, to stay the processes of decay to which the contents of the vault are subject.

Typically I include with the body and within the vault a quantity of calcium carbide. When a burial is made the air inclosed within the vault is brought to and maintained at a relatively constant temperature—a temperature that ordinarily is lower than the temperature of the air at the moment of closing. A new vapor balance is established, and there is precipitation of moisture from the inclosed body of air. Such precipitated moisture coming into contact with the calcium carbide reacts and produces acetylene gas. Another source of water within the vault is the body itself; from it, in course of time, water escapes, to accumulate in the bottom of the vault. And this water, too, coming into contact with carbide of calcium, will effect the generation of acetylene. A third source of water, in particular instances, may be from without: water rising outside and overcoming the water seal (to the extent that the air alone is the effective seal-maintaining agent) 60 may pass over the flange 2 and enter the vault. If the so-entering water has immediate access to carbide of calcium, acetylene gas will be generated; and it may be so generated in quantities sufficient substantially to augment the pneumatic pressure within the vault and to prevent further ingress of water, even should the water externally of the vault rise to still higher level. If then the body or the body-containing casket be arranged within the vault at a level somewhat above the 65 rim of flange 2, water that has so entered will not gain access to it.

Acetylene gas has recognized preservative properties. It inhibits the growth of aerobic organisms.

Referring to the drawing, the vault is preferably formed of cast-iron, and consists of two castings. Formed integrally with the base or floor-plate 1 are the flange 2, and the cross-bars 3. The cover 4 is indeed a bell, and comes to position resting by its margin upon plate 1 and closely surrounding by its margin the flange 2. These castings are impervious, and the burial vault is practically indestructible by ordinary agencies of corrosion. The line A—B upon the drawing is intended diagrammatically to indicate a level to which water may rise in the ground in which the vault rests. In such circumstances the air-seal described becomes effective.

Among other materials that may be employed 110

to afford added volumes of gas I would name aluminum carbide, which reacts with water to produce methane; and metallic sodium and metallic potassium react with water and afford free hydrogen.

The seal against ingress of water to a vault of air-seal type cannot be regarded as permanently effective. That is to say, when water has risen externally of a vault to a level such as to render the body of air within the vault effective in the manner described, a process of absorption sets in—a penetration of the air into the adjacent body of water and a consequent creeping in of the tide of water, until at length the seal becomes less effective, and water gradually accumulates within and fills to greater and greater degree the vault chamber. This, to be sure, is a very gradual, nevertheless a very certain, natural process. The generation within the vault of additional volumes of gas, as is accomplished in the

practice of my invention, has the incidental consequence and effect of prolonging the period and, with proper attention, prolonging in very substantial degree the period during which the vault and its contents will continue secure against ingress of moisture, even in water-soaked ground.

I claim as my invention:

In the art of preservation, wherein a corpse is disposed within a vault of air-seal type and the vault is buried in water-soaked ground, the method herein described of increasing the efficacy of the seal and prolonging the period of security of the corpse from the access of water which consists in building up and replenishing within the vault gaseous pressure by reaction of material enclosed within the vault at the time of burial with moisture within the vault, whereby such augmentation becomes continuously effective in the prevention of ingress of water.
